John Dohmann
Design for the handles of Spoons &c.
Chas Schmid

John Dohmann

United States Patent Office.

JOHN POLHAMUS, OF NEW YORK, N. Y.

Design No. 2,954, dated March 17, 1868.

DESIGN FOR THE HANDLE OF A FORK OR SPOON.

The Schedule referred to in these Letters Patent and making part of the same.

TO ALL WHOM IT MAY CONCERN:

Be it known that I, JOHN POLHAMUS, of the city and State of New York, have invented or produced a new and original Design for Handles of Forks, Spoons, &c.; and I do hereby declare the following to be a correct description of the same, reference being had to the accompanying photograph of a spoon, the handle of which contains my said new design.

The lower part, *a*, of the handle is plain and rounded. The beads and knobs, at *b*, commence the design. From this, along the handle towards the end, the leaf design *c* diverges, and receives the base of the scroll-work *d*, with the flowers at *e*. The end of the handle is ornamented with diverging beads, forming a leaflet pattern at *f*. The ground-work between the scrolls is ornamented with corded work.

What I claim, and desire to secure by Letters Patent, is—

The design of the ornamentation for the handles of forks and spoons, as represented.

In witness whereof, I have hereunto set my signature, this thirteenth day of February, 1868.

JOHN POLHAMUS.

Witnesses:

GEO. D. WALKER,
CHAS. H. SMITH.
